[57] CLAIM

The ornamental design for a combined compartmented bottle and closure, as shown and described.

DESCRIPTION

FIG. 1 is an isometric view of a combined compartmented bottle and closure showing my new design;

FIG. 2 is a front elevation thereof;

FIG. 3 is a top plan view thereof;

FIG. 4 is a bottom plan view thereof;

FIG. 5 is a right side elevation thereof, the left side elevation is a mirror image;

FIG. 6 is a fragmentary isometric view showing the closure in an open position;

FIG. 7 is a fragmentary rear elevation of FIG. 2, the portion of the bottle that is not shown is identical to the front of the bottle shown in FIG. 2;

FIG. 8 is an isometric view of the compartmented bottle shown with a modified form of the closure;

FIG. 9 is a fragmentary isometric view of FIG. 8 with the closure shown in an open position; and,

FIG. 10 is a fragmentary rear elevation of FIG. 8.

FIG. 1.

FIG. 3.

FIG. 2.

FIG. 5.

FIG. 6.

FIG. 4.
